Claim 12 recited, that the rear panel 32 is joined to the front panel 34 by a fold line 33, and that the front panel 34 is joined to the rear panel 32 by a fold line 31, is hereby amended to read: "that the rear panel 32 is joined to the front panel 34 by a fold line 33, and that the front panel 34 is joined to the rear panel 32 by a fold line 30, which are alined with the fold line 29, and connected with the panel 32 by a fold line 31, which is alined with the fold line 29."

UNITED STATES PATENT OFFICE

2,527,028

DISPLAY CONTAINER

Harold L. Myers, Morristown, N. J.

Application July 8, 1948, Serial No. 37,623

6 Claims. (Cl. 206—45)

1

This invention relates to display containers having front and rear compartments.

An object of the invention is to provide a display container with a plurality of compartments which are adapted to be arranged particularly compactly for shipping and storage, but to occupy a highly effective angulated position for the display of goods. A further object is the provision of a device wherein one or more rear articles are effectively displayed beyond the top of one or more effectively displayed front articles. Another object is the provision of a structure which assumes its display position with a minimum of effort or attention on the part of the person unpacking it for display.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description taken in connection with the accompanying drawings, in which:

Figure 1 is a perspective view of a display container embodying the invention and in display position;

Fig. 2 shows one of the blanks from which the container is formed;

Fig. 3 shows the other blank;

Fig. 4 shows the blanks of Figs. 2 and 3 in assembled relationship;

Fig. 5 shows the opposite side of the assembly; and

Fig. 6 shows the assembly in position for shipping or storage and surrounded by a cover.

The particular construction exemplified is formed from two blanks as shown in Figs. 2 and 3. The blank of Fig. 2 comprises a panel 10 to which is connected by a fold line 11 a flap 12 joined by a fold line 14—15 to a tuck 16. The portions 14 and 15 of the fold line are separated by a slit 17. Connected to the panel 10 by a fold line 18 is a flap 19 adapted to receive glue on an under surface as shown at 20 in Fig. 5; and connected to the panel 10 by a fold line 21 is a panel 22. Connected to the panel 22 by a fold line 23 is a tab 24, and by a fold line 25 is a panel 26 and which is joined by a fold line 27 to a tab 28 having therein a fold 29. Connected to the panel 26 by fold lines 30 and 31, which are alined with the fold line 29, is a panel 32, and connected with the panel 32 by a fold line 33 is a panel 34.

Connected with the panel 34 by means of a fold line 35 is a tab 36 and by means of a fold line 37 is a tab 38. Connected with the panel 26 by a fold line 41 is a panel 42 adapted to be glued to the flap 19 by means of glue 20. Connected with the panel 42 by a fold line 44 is a tab 45. Connected with the panel 26 by a fold line 46 is a panel 47 which is separated from the panel 22 by a cut 48 and from the panel 42 by a cut 49. Connected with the panel 47 by a fold line 51 is a panel 52 and connected therewith by a fold line 53 is a tab 54 having therein a fold line 55 which is alined with the free edge of the panel 52. Connected with the panel 52 by a fold line 57 is a panel 58, and connected with the panel 58 by a fold line 59 is a tab 60. Connected with the panel 52 by a fold line 61 is a panel 62 which is joined by a fold line 63 to a panel 64 and by a fold line 65 to a panel 66. Connected with the panel 66 by a fold line 67 is a flap 68 adapted to receive glue 69 as shown in Fig. 5 to join it with the flap 58. Connected with the panel 66 by a fold line 71 is a panel 72, and connected with the panel 72 by a fold line 73—74 is a flap 75. A slit 76 is cut centrally between the fold lines 73 and 74.

The blank of Fig. 3 comprises a panel 80 joined by a fold line 81 to a panel 82 which is joined by a fold line 83 to a panel 84, which in turn is joined by a fold line 85 by a flap 86.

The blank of Fig. 3 is assembled with the blank of Fig. 2 by having the flap 86 bent over onto the panel 84 and by having inserted thru the sections 86, 84, and 10 fastening means such as wire staples 87 and 88 and by having inserted thru the panels 84 and 10 fastening means such as wire staples 89, 90, and 91. The assembly thus provided is illustrated in Figs. 4 and 5 and is readily adapted to be converted into display container form by folding on the fold lines and by the gluing at 20 and 69. In assembly, the panel 42 is joined to the flap 19, and the panel 58 to the flap 68, as by gluing; the tabs 24 and 45 are bent in; the panel 12 and the tuck 16 are bent in on the fold lines 11 and 14—15 respectively; and the tab 28 is bent on the line 29 and inserted in the slit 17. The tabs 60 and 64 are bent in, the panel 72 and the tuck 75 bent in on the line 71 and 73—74 respectively, and the tab 54 bent on the line 55 and inserted in the slit 76. The panel 52 may then be folded down on the line 51.

Thus assembled the display container includes a rear compartment 92 adapted to receive articles 93 for display above upper edge of the panel

26, and a front compartment 94, which, in the present instance, is of similar capacity and which is adapted to display articles 93 over the wavy edge of the panel 66. For shipping purposes the front and rear compartments are disposed in parallel as shown in Fig. 6, with the panel 32 bent up and the panel 34 bent down between the panels 10 and 26; the tabs 36 and 38 lying between the panel 52 and the panel 72 in the space at either side of the tab 54. The panels 82 and 80 are folded over on lines 83 and 81 respectively to permit the free end of the panel 80 to be thrust behind the panel 66. The assembly is preferably surrounded by a cover 95 extending over the front, rear, top, and bottom of the assembly but leaving the ends open so that the assembly can be readily slid out from the cover to display the goods for sale. Upon the removal of the cover, or upon unpacking if no cover is used, the free end of the tab 80 may be thrust under the flap 86 to provide a display back. The front compartment moves forward to permit the panels 32 and 24 to unfold. The articles in the front compartment are thus displayed at an angle and at a point below the top of the articles in the rear compartment to provide a very slight and effective display arrangement.

Since certain changes may be made in the above article and different embodiments of the invention could be made without departing from the scope thereof, it is intended that all matter contained in the above description or shown in the accompanying drawings shall be interpreted as illustrative and not in a limiting sense.

I claim:

1. A display container comprising foldably-connected rear, side, and front panels, a bottom flap and overlapping mutually-joined side flaps providing a rear compartment; and rear, side, and front panels and a bottom flap and overlapping mutually-joined side flaps providing a front compartment; said container being formed from a blank wherein the front and rear panels of the front compartment are longitudinally connected, the front and rear panels of the rear compartment are longitudinally connected, and the front panel of the rear compartment and the rear panel of the front compartment are laterally connected; and a blank secured to the rear panel of the rear compartment and providing a panel foldably connected with the rear panel of the rear compartment and a panel foldably connected thereto and adapted to be thrust behind the front panel of the front compartment when the assembly is arranged in shipping position and against the rear panel of the rear compartment when the assembly is arranged in display position.

2. A display container comprising foldably-connected rear, side, and front panels, a bottom flap and overlapping mutually-joined side flaps providing a rear compartment; and rear, side, and front panels and a bottom flap and overlapping mutually-joined side flaps providing a front compartment; said container being formed from a blank wherein the front and rear panels of the front compartment are longitudinally connected, the front and rear panels of the rear compartment are longitudinally connected, and the front panel of the rear compartment and the rear panel of the front compartment are

laterally connected; and a blank secured to the rear panel of the rear compartment and providing a panel foldably connected with the rear panel of the rear compartment and a panel foldably connected thereto and adapted to be thrust behind the front panel of the front compartment when the assembly is arranged in shipping position and against the rear panel of the rear compartment when the assembly is arranged in display position; the second-mentioned blank comprising a flap folded upwardly and secured in folded position to provide a pocket for the reception of the second-mentioned panel of the second-mentioned blank when in its second-mentioned position.

3. A display container comprising a rear compartment, a front compartment, a connector portion foldably attached to the rear side of the front compartment at an upper point and foldably attached to the front side of the rear compartment at an upper point, the distance between the base of the front compartment and the first-mentioned point being greater than the distance between the base of the rear compartment and the last-mentioned point to enable said compartments to be moved between a generally parallel shipping position and an angulated display position in which the rear compartment holds a perpendicular position and the front compartment a rearwardly-leaning position, and a connector portion foldably attached to the rear compartment at a forward basal point and foldably attached to the front compartment at a rearward basal point to limit such movement.

4. A display container as set forth in claim 3 wherein the last-mentioned connector portion comprises a basal panel and two tabs foldably connected to said basal panel and adapted to extend upwardly to lie against the inside of the rear panel of said front compartment and to support the same securely when in display position.

5. A display container as set forth in claim 3 wherein the rearward panel of the front compartment has at its base a centrally located tab foldably connected to the end of said panel and adapted to be inserted into a rearwardly located slot between the two first-mentioned tabs on the basal panel of the front compartment, to lie against said basal panel and to lock and support said compartment securely when in display position.

6. A display container as set forth in claim 3 wherein an open-ended shipping cover comprising only front, rear, top, and bottom panels is slidably removably-mounted over the aforesaid elements when in shipping position.
